UNITED STATES PATENT OFFICE.

ROBERT C. COLE, OF WEST HARTFORD, CONNECTICUT, ASSIGNOR TO THE JOHNS-
PRATT COMPANY, OF HARTFORD, CONNECTICUT, A CORPORATION OF CONNECTICUT.

COMBINED FUSE CONTACT-CLIP AND TERMINAL HOLDER.

1,025,245.

Specification of Letters Patent.

Patented May 7, 1912.

Application filed May 4, 1911. Serial No. 624,986.

To all whom it may concern:

Be it known that I, ROBERT C. COLE, a citizen of the United States, residing at West Hartford, in the county of Hartford and State of Connecticut, have invented the following described Improvements in Combined Fuse Contact-Clips and Terminal Holders.

The object of the invention is to provide 10 an efficient and cheaply constructed fuse clip and line terminal strap from a single piece of sheet metal, and in which the clamping screw for the strap is arranged transversely to the plane of the fuse block, where- 15 by uninterrupted metallic and electrical continuity will be obtained from the line to the fuse, and whereby the clamping and un- clamping of the line terminal can be accom- plished with the least inconvenience.

20 To this end the invention consists in the shape of the blank from which the device is struck up, and the form and relative ar- rangement given to the several parts of the device.

25 The invention also includes the details of the construction hereinafter pointed out; and particularly the arrangement of a lip or flange on the line clamping strap for preventing disalignment of the screw holes, 30 which latter feature, as will be later ob- served, is capable of employment in other forms of fuse clips than the one herein set forth.

The above and other features of the in- 35 vention will more fully appear by reference to the accompanying drawings in which—

Figure 1 is a view in side elevation of a combined fuse clip and line terminal strap embodying the present invention, a line con- 40 ductor terminal being indicated in position in the strap. Fig. 2 is a view of the strap and line terminal taken on the line 2—2 of Fig. 1. Fig. 3 is a view of the fuse clip taken on the line 3—3 of Fig. 1. Fig. 4 45 shows the blank from which the combined fuse clip and terminal strap is struck.

Referring to Fig. 4 the blank is formed 50 of sheet metal with two rectangular por- tions 1 and 2 connected by a neck 3 located centrally of the part 1 and somewhat to the one side of the middle of part 2, so that the latter is of greater extent on one side of the axis of the neck than on the other. Part 1 of the blank is the part from which the clip 55 which holds the fuse is struck. A central

section 4 forms the base of the clip and is perforated with holes marked 20 for at- tachment to a fuse base block of insulating material. Its end sections 6 are bent up- 60 wardly to form the parallel and upright clip contacts, and its sections 5 intermediate of the portions forming the base and clip con- tact sections are curved upwardly and also inwardly as shown in Fig. 3 whereby the 65 contact sections 6 are maintained in parallel proximity to each other and with a sufficient degree of resilience to accommodate a fuse terminal thrust between them. The extremi- 70 ties of the clip sections 6 are turned out- wardly to form diverging lips 7 to guide the 75 terminal contact of the fuse into place, and a tongue 8 is stamped out of one of the clip sections and turned in between the clips to form a stop for the blade of the fuse, it being understood that the particular form of clip 75 taken for illustration herein is adapted for use with cartridge fuses having projecting contact terminals of the familiar knife- blade type.

The middle section of part 2 of the blank, 80 together with a considerable portion of its longer wing 9, is rolled over to form a con- tractible clamp or strap member 10 of sub- stantially cylindrical shape as indicated in Fig. 2, and adapted to receive the terminal 85 thimble of the line wire of the circuit in which the fuse is to be placed. The oppo- site shorter wing of the part 2, as well as the longer wing, terminate in substantially flat 90 surfaces which project laterally from the thimble receiving portion at some distance, one from the other, and are substantially parallel to one another and to the plane of the clip base 4 above referred to. Finally the end of one of the wings of the part 2, 95 preferably the end of the wing 9, is turned inwardly toward the other in the form of a flange or lip marked 12 in the drawings, which lip is substantially vertical to and is adapted to bear against the opposing end 100 of wing 11. The two strap sections 9 and 11, as thus arranged, are provided with alined screw-holes 14 and 15, the screw- 105 hole 14 in the lower section being threaded so that by means of a screw 16 the two ends of the strap may be drawn together and thereby tightened on the thimble 17 of the line terminal 18. The flanged lip 12 by its bearing upon the under strap terminal, pre- 110 vents relative lateral slip of the two por-

tions of the strap and tends to maintain the axis of the two screw-holes in substantial alinement during the operation of tightening the screw and drawing the strap ends together.

The device as thus constructed is adapted for mounting upon a usual base-block 13 by means of screws such as shown in Fig. 1 which are screwed into the holes 20 in the 19 base section 4 of the clip. It will be observed that the arrangement of the perforated portions 9 and 11 of the clamping strap in substantial parallelism with the base-block 13 enables the clamp screw 16 to have a perpendicular position with respect to the latter whereby it can be readily operated. This arrangement is of particular advantage with 15 fuse-blocks which are placed in the bottom of a box or casing such as indicated at 20 in Fig. 1.

Claims.

1. A combined sheet metal fuse clip and line terminal strap formed from a blank having two parts with a neck connecting 25 said parts, one of said parts being shaped into two opposing spring clips and the other being shaped to form the strap for the

line terminal, the strap-forming part having wings of unequal length from the axis of the device, whereby the longer wing may 30 embrace the line terminal and thence be opposed to the shorter wing so that the two wings may be clamped together by a screw disposed perpendicularly to the base block on which the device is mounted.

2. A sheet metal line terminal strap for fuses, said strap having a portion intermediate the ends thereof shaped to embrace the line terminal and having the ends thereof opposed, and substantially parallel, with 40 alined screw holes therein, a flange or lip carried by one of the end portions perpendicular to the other end portion to prevent disalinement of the holes when the strap is tightened, and a screw passed through the 45 alined screw holes for tightening the strap on the line terminal.

In testimony whereof, I have signed this specification in the presence of two witnesses.

ROBERT C. COLE.
